(57) **CLAIM**

We claim the ornamental design for the light therapeutic device, as shown and described.

DESCRIPTION

FIG. 1 is a perspective view of a light therapeutic device showing our new design in accordance with a first embodiment;

FIG. 2 is a top plan view thereof;

FIG. 3 is a bottom plan view thereof;

FIG. 4 is a side elevational view thereof;

FIG. 5 is a front elevational view thereof;

FIG. 6 is a rear elevational view thereof;

FIG. 7 is a perspective view thereof, shown in separated condition; and,

FIG. 8 is a side elevational view thereof.
